COLORADO, A CORPORATION OF COLORADO.

ENDLESS BLANK-GRIPPING APRON CONVEYER.

1,244,536.

Specification of Letters Patent. Patented Oct. 30, 1917.

Application filed February 8, 1916. Serial No. 76,989.

To all whom it may concern:

Be it known that we, MELVILLE E. PETERS, GEORGE H. FATH, and ALBERT F. MILLER, citizens of the United States of America, residing at the city and county of Denver and State of Colorado, have invented a new and useful Endless Blank-Gripping Apron Conveyer, of which the following is a specification.

10 Our invention relates to an improved endless blank gripping apron conveyer, and the objects of our invention are:

First, to provide means for gripping and conveying blanks in either a wet or dry 15 condition and for freeing them at a predetermined part of the conveyer from which they may be advanced to further treatment.

Second, to provide means including an endless apron conveyer for gripping blanks 20 and conveying them to further treatment; and

Third, to provide a simple blank gripping, conveying and releasing mechanism that is 25 adapted to grip and convey gummed or dry blanks from gumming mechanism or from dry blank feeding mechanism.

We attain these objects by the mechanism illustrated in the accompanying drawings, in which:

30 Figure 1, is a side elevation of a machine equipped with our improved endless blank gripping apron conveyer and mechanism connected therewith.

Fig. 2, is a plan view of the same.

35 Fig. 3, is a front view of the transmission cylinder, showing in connection therewith one of the bars supporting the blank grippers and operating mechanism connected therewith.

40 Fig. 4, is an end view of the transmission cylinder, the gripper bar and its grippers, and mechanism for holding the grippers open.

Fig. 5, is a plan view of a portion of the 45 parts shown in Fig. 4, the cylinder being shown in section.

Fig. 6, is a side view of the blank releasing mechanism, and

50 Fig. 7, is a plan view of the parts shown in Fig. 6.

Similar letters of reference refer to similar parts throughout the several views.

Referring to the drawings,—

The numeral 1 designates an endless trav-

eling conveyer, which is made up of our 55 blank gripping aprons. This endless gripping apron conveyer consists of endless side sprocket wheel chains 2 and the aprons 3 and grippers 4 and their operating mechanism.

Our present invention is especially adapted to receiving gummed blanks such as are 60 adapted to be used for covering paste board boxes, from a gumming cylinder or drum in the manner illustrated and described in our pending application Serial No. 30471 filed May 25, 1915, for a pneumatically controlled automatically operating blank gumming and tempering machine, but it is also

adapted to grip gummed blanks from any 65 kind or character of blank gumming mechanism whether a cylinder or cylinders or a flat pressure type of blank gumming mechanism, or any other type of blank gummer that leaves the blank in such a manner that

70 the apron grippers can grip an edge of it. Consequently the type or character of mechanism that gums the blanks and delivers them in operative relation to our gripper mechanism is immaterial and forms no 75

part of our present invention. Our invention is also adapted to receive and grip and convey dry or ungummed blanks or blanks 80 that are made of any material, such as paper, silk, or thin leather, that are fed to it by any blank feeding mechanism. Consequently our invention will grip and convey blanks made of any material and that are

85 in any suitable condition as to their surfaces or of any shape suitable to be gripped and conveyed by our blank gripping and conveying apron. Consequently either dry or wet or blanks gummed on one side

90 can be fed to our gripper apron and can be conveyed any predetermined distance and 95 be freed and picked up and advanced to further treatment in box wrapping or covering machines or in printing presses or in cutting and forming presses or machines.

This endless blank gripper apron traveling conveyer is provided with intermittent driving and stopping mechanism that controls its traveling movement. The intermittent stop periods of the conveyer only take place to allow the blanks to be gripped by an air suction mechanism that lifts them off from the conveyer, which air suction mechanism we do not illustrate, and the

point in this endless conveyer's intermittent movement where these stops take place to allow the blanks to be removed from it, constitutes its blank releasing station, and this 5 station is preferably positioned at the rearward end of the traveling movement of the conveyer's upper or top portion, but may be positioned at any practical point in its length.

10 The endless sprocket chains of our endless conveyer are mounted on three sprocket wheels 5, 6 and 7 which are secured on shafts that are journaled in the side frames of the machine to which our gripper apron is 15 attached. The machine itself, however does not form a part of our invention and is not illustrated. At the blank receiving and gripping end of our gripper apron blank conveyer a cylinder 8 is mounted on the shaft 9. This cylinder we term the transmission cylinder. This transmission cylinder is a hollow cylinder and is provided with a large gap in its peripheral surface which extends across it from end to end. 20 This transmission cylinder rotatively supports cooperatively with a pair of sprocket wheels 5 which are mounted on its shaft at the opposite ends of the cylinder, an endless conveyer belt which is provided with cross bars 10 and 11, that are spaced at a distance apart that is a little greater than the largest size blanks that are to be run through the machine, each cross bar of which enters the gap in this cylinder. The endless conveyer 25 comprises a pair of endless chains 2 mounted on sprocket wheels and cross bars extending across from one chain to the other and connected to them, and sheets of any suitable material but preferably of a water absorbing fabric, preferably canvas, are secured between the cross bars at close but predetermined distances apart, the sheets of fabric being larger than the largest blanks the machine will gum. The conveyer also 30 comprises means for picking up at about the longitudinal center of the transmission cylinder which we term its blank receiving station, and conveying in a straight horizontal line over guide rails 12, the blanks while 35 they are resting on the canvas aprons, and carrying them to the rear end turning point of the conveyer, which extends over the sprocket wheels 6, and the blanks are released at this turning point by mechanism 40 that opens the blank gripping fingers, and just before the blank gripping fingers are opened the conveyer stops and the blank is then gripped by air suction tubes, and instantly afterward the grippers are opened 45 and the blanks are removed from the conveyer, and the point in the traveling movement of the conveyer where it stops and the blank is removed from it we term the blank releasing station. The conveyer is stopped 50 during each revolution of its transmission

cylinder 8 by any suitable means. We preferably use, however, for this purpose an intermittently rotating spur gear 13, that is secured to the shaft 9 that supports the transmission cylinder 8 and that is driven by a 55 spur gear 14. Consequently the conveyer stops at its blank releasing station for only a few seconds once in each revolution of the gumming cylinder and of the transmission cylinder, as will be more fully described 60 hereinafter. The supporting members of the conveyer are two block link type of chains 2 that are of even length and are mounted on the sprocket wheels 5 at its blank receiving end, and on sprocket wheels 6 at its discharge end. These chains are supported and run on guide rails that are secured to the side frames of the machine by bolts 15. The bottoms of these chains extend 65 downwardly and forwardly from the sprocket wheels 5 and 6 and around sprocket wheels 7 which are mounted in vertically adjustable bearings which may be of any suitable construction, and from these wheels they extend up over idle sprocket wheels 16 70 to the transmission cylinder, and its forward end supporting sprocket wheels 5. These two chains are connected together by the cross bars 10 and 11 of iron or other suitable material, which are provided with end 75 flanges that are secured to the adjacent sides of the link members of the chain. To the bar 11 is secured one end of a sheet of water absorbing fabric 8, which may be of any suitable material. We preferably use however sheets or aprons of canvas wrapped around and sewed or otherwise secured around or to the bar. The bar 10 supports the opposite end of the fabric or canvas 80 apron, which is fastened to it by a cleat 17 85 and by screws 18 that extend through the cleat into the bar and clamp the apron between the cleat and the bar. On the opposite side of the bar 10 from the belt a rod 19 is journaled in clips 20 that are formed on the 90 side of the bar. One of these clips 20 is provided with a lug that forms a bearing for a rock arm pawl 21 which engages a ratchet tooth that is formed on a ratchet wheel 22 95 that is secured on the rod 19. This pawl is provided with a side stem 23 that extends through the lug of the clip and on its end a coiled tension spring 24 is placed and is arranged and adapted to hold the pawl in 100 engaging relation to the ratchet tooth of the wheel 22. The lower end of this rock arm pawl is provided with a roller 25 that is arranged and adapted to engage a cam 26 that is formed on the end of a fixed link member 105 27 that is mounted loosely on the shaft 9 of the cylinder. This cam provided link member is bolted at its opposite end from its cam to the adjacent side frame of the machine. The rod 19 on the cross bar 10 of the endless conveyer, is also provided with a plurality 110

of finger pickers 4. These are secured to the rod to stand with their flat ends 28 directly against the edge of the cross bar 10 upon which their shaft 19 is mounted. A sufficient number of pickers is used to tightly clamp the edges of the blanks against the cooperating edges of the bars 10; and they are actuated by a coiled spring 29 which is mounted on the rod 19 and is arranged and adapted to normally hold the pickers under constant resilient tension against the edge of the bar 10. These picker fingers are locked in their open position by the pawl 21 engaging the ratchet tooth of the wheel 22 when the pickers are thrown open, in a manner to be presently described, at the discharging point of each blank from the conveyer.

When the pickers grip and clamp a blank as their edges are exposed on a gumming cylinder in cases where a cylinder is used to gum the blanks, they peel it off in the direction in which it would naturally curl up when first removed from the gumming cylinder, and they are enabled to do this when both cylinders travel at the same speed as they should, and their adjacent surfaces in the same upward direction, and consequently although neither the transmission cylinder nor the conveyer stops for the pickers to grip the edge of each blank, the transmission cylinder leads and peels each blank off of the gumming cylinder, and as the pickers carry each blank up over the transmission cylinder, it lays each blank out flat on the adjacent canvas apron, which when tempered blanks are required is moistened with water and which, as it is conveyed along, moistens it to a limpid or as it is termed a tempered condition, which means that both sides of the blank are in the same moistened condition and that the blank will not curl up in either direction, but will remain in a flat straightened out position.

In order to prevent the chains of the conveyer belt from jumping off from the sprocket wheels when the roller 25 strikes against the cam 26 as the chains travel along, and the picking fingers are freed by the pawl 21 and strike violently the bar 10 as they grip the edge of each blank, which action of the roller striking the cam and of the picker fingers striking the bar takes place almost simultaneously, we provide a pair of guide plates 30, placing them on opposite sides of the machine, and arranging them to register close to the edge of the sprocket wheels 5 so as to prevent the chains from jumping off from the teeth thereof.

In order however that the picker fingers shall be positively actuated to fly open to release blanks at the discharge end of the conveyer, a segment toothed lever is arranged to be moved to partially rotate a segment gear 31 on the rod 19 of the bar 10

quickly, in each cycle movement of the transmission cylinder. The segment toothed lever is driven from a shaft 32 of the machine to which our gripper apron conveyer is attached. For this purpose a sprocket wheel 33 is mounted on a shaft 3^A of the machine upon which a sprocket chain 34 is mounted that extends to and drives a sprocket wheel 35 that is mounted on the shaft 32 that is journaled in bearings secured on the side frames A and B.

Upon the shaft 32 a cam 36 is mounted, which engages a roller 37 that is mounted on one end of a rock arm 38, the opposite end of which is connected to one end of a connecting rod 39. This rock arm 38 is pivotally connected intermediate of its ends to the side frame A by a bolt 40. The opposite end of the connecting rod is pivotally connected to one end of a rock arm 41, the hub portion of which is mounted on a stud pin 42 that is secured to the adjacent side frame of the machine. The opposite end of the rock arm is pivotally connected to one end of a link 43, the opposite end of which is pivotally secured to a segment toothed lever 44. Consequently the shaft 3^A of the machine drives through the medium of the chain 34, the cam 36, the rock arm 38, connecting rod 39, the rock arm 41, and 95 the link 43, the segment toothed lever 44, and the segment gear 31, on the rod 19, to open the finger pickers and release each blank, and just prior to this the conveyer and the transmission cylinder are stopped 100 through the engagement of the blank toothed portions 45 and 46 of the spur gears 13 and 14 respectively, which come together and stop the transmission cylinder for a few seconds, while the blank on the apron at the 105 releasing station of the conveyer is gripped and lifted and removed by air suction blank advancing tubes, or any other mechanism.

Each one of the fabric aprons or panels or sheets of canvas of the conveyer belt is 110 positioned separately and independent of the others, and they are positioned at such a relative distance apart as will allow them to meet and receive each blank as it is grabbed by the picker fingers, and each one 115 of these sheets of canvas is moistened by water in some form as it travels along the under side portion of the conveyer, in case it is desired to temper the under side of gummed blanks. Where dry blanks are fed 120 to our gripper apron it is not necessary to temper them, but where gummed blanks are used we deem it essential that they be tempered.

There are a number of ways in which 125 water in some form can be imparted to each of these sheets of canvas. We preferably however carry out this feature of our invention in the following manner:

Between the side frames we place and 130

support a dish 47 by any suitable means, and in the dish we place a wick 48, which is arranged to extend over the edge of the dish and to bear against the surface of the transmission cylinder, and the capillary and absorbent action of the water on the wick feeds the water through the wick to its outside looped end which feeds off from the wick onto the surface of the cylinder and 10 keeps its surface wet, as a wick should be used that is wide enough to keep enough of the surface of the transmission cylinder wet to moisten the full width of the canvas, or at least enough of it to moisten the 15 full width of the size of blanks being run through the machine.

Then as the conveyer belt travels rotatively along each fabric or canvas panel when it reaches the transmission cylinder 20 and travels around it is wrapped tightly against its circumferential surface, and is thus moistened on its under side from that on which it receives the blanks from the gumming cylinder, and each blank as it 25 is grabbed by the finger pickers is peeled off of the gumming cylinder and is rolled out flat against the moistened surface of a moistened canvas panel. Consequently by the time each blank reaches the end of its 30 rearward travel, it is in a flat limpid tempered condition.

It is necessary that a mechanism be employed for cleaning or wiping off the blank engaging faces of the blank gripping finger 35 pickers, between each of their blank gripping, carrying and releasing operations when they are engaging the gummed surface of blanks, and we preferably carry out this feature of our invention as follows:

40 A plurality of arms 49 are mounted on a rock shaft 50 which is journaled in adjustable frames 51 on the ends of a receptacle or box 52. The free ends of these arms are provided with flexible pads or wipers 53 which normally are in contact with cleansing liquid contained in the receptacle 52. The rock shaft is equipped at one end with a crank arm 54 which is slidably connected with one end of a rod 55, whose opposite 45 end is connected with the inner end of a lever 56, which is fulcrumed intermediate of its ends to the frame. This lever is actuated to swing the wipers into operative position by means of a spring 57, one end of 50 which is connected with the inner end of the lever, while its opposite end is connected with the adjacent side frame, as shown. The outer end of the lever 56, carries a roller 58, which is engaged by a cam 55 disk 59, on the driving shaft 3^A. This disk has a cam face 60, which engages the roller 58 at a predetermined time, or after each momentary pause of the conveyer, and thereby rocks the lever 56, by which the rod 55 60 imparts an upward movement to the lever

54, which rocks the shaft 50 by which the arms 49 are submerged in the water in the receptacle 52. However, when performing the finger-cleansing function, the cam projection 60 of the cam disk 59 releases the 70 antifrictional roller 58 carried by the lever 56, and the spring 57 actuates the said lever to cause the rod 55 to move in the direction of the arrow (see Fig. 1), whereby the flexible cleansing extremities of the wiper arms 75 are brought into wiping contact with the gripping surfaces of the fingers 4 of one set of gripping mechanism, which cleanses the blank engaging faces of the fingers of their gummed or sticky condition. As soon 80 as this has occurred, the cam projection of the cam wheel 59 moves into engagement with the roller 58 of the lever 56 and rocks the same to move the rod 55 in the direction opposite that indicated by the arrow, 85 which returns the arms 49 to their normal position, whereby their flexible members 53 are again returned to the cleansing liquid in the pan. This cleansing operation of the fingers takes place during the stop period 90 in the travel of the conveyer.

There are a number of ways in which water can be applied to the under side of the canvas aprons and this tempering feature does not form a part of the present 95 invention, which is confined to the blank gripper apron endless conveyer.

In operation blanks either with a gummed or ungummed surface are fed to our gripper apron's transmission cylinder by suitable 100 mechanism and they are gripped by the picker fingers and as they are carried up over the transmission cylinder they are laid out flat against the top surface of the apron of the grippers that hold them and they are 105 conveyed to their releasing station by an intermittent traveling movement which may be imparted to the conveyer by any suitable mechanism, and when the conveyer stops at its blank releasing station the blank is released from the picker fingers and is picked up and forwarded for further treatment to 110 the machine for which it is intended.

Our invention provides a simple and reliable blank gripper apron conveyer, and 115 while we have illustrated the preferred construction and arrangement of it we do not wish to be limited to the construction and arrangement shown and described, as many changes might be made without departing 120 from the spirit of our invention.

Having described our invention, what we claim as new and desire to secure by Letters Patent is:

1. In a blank gripping apron conveyer, 125 the combination with an intermittently traveling movement canvas apron conveyer arranged to receive each blank upon each apron during its traveling movement, each apron of said conveyer being provided with 130

- a transverse row of cam and spring controlled blank gripping fingers, means including cam and toothed segments for releasing the gripping fingers from the blanks 5 during the stopped period of the conveyer, means including gearing for intermittently moving said conveyer, and means including a cam actuated pawl for releasing said grippers to grip a blank at a predetermined 10 point in said conveyer's intermittent traveling movement.
2. In a blank gripping apron conveyer for blank gumming mechanism, the combination of an endless traveling apron conveyer 15 arranged to receive the blanks upon its aprons from a blank gumming mechanism, each apron of said conveyer being equipped with a number of sets of gripping devices adapted to respectively and successively engage the blanks to facilitate their removal 20 from the gumming mechanism, each set of blank grippers comprising a spring-actuated rod, angled flat-ended gripping fingers mounted thereon and adapted to clamp each 25 blank against a cross-bar of each apron, means including cam actuated toothed segments for moving said grippers to release each blank, means including a spring actuated pawl for locking the said blank gripping fingers in their open position, means 30 including a cam for releasing said fingers to cause them to grip a blank at the gumming mechanism, and means for automatically unlocking the fingers to release the 35 blanks.
3. In a blank gripping apron conveyer, the combination of an endless canvas traveling conveyer provided with a hollow supporting and transmission cylinder at its blank receiving end, said transmission cylinder being provided with a gap transversely of its length through its surface into its interior, arranged to receive the several portions of the conveyer as it travels around it, each canvas 40 apron of said conveyer being equipped with a transverse row of flat ended spring and cam actuated blank gripping fingers adapted to respectively and successively engage the blanks when in the gap of said transmission cylinder, means including a cam actuated pawl for releasing each row of said fingers to grip a blank, and means including cam actuated lever and toothed segment members for moving each row of fingers to 45 release each blank from each apron when said gripping devices are in the gap of the transmission cylinder.
4. In a blank gripping apron conveyer, the combination with the conveyer comprising 50 separated and independent fabric aprons, each apron being supported in said conveyer by cross bars and the hollow gapped transmission cylinder of the spring and cam actuated blank gripping devices attached to 55 each apron comprising a cross bar, a spring-actuated rod mounted on said bar, gripping fingers mounted on said rod, said gripping fingers comprising an angled end arranged to grip each blank against a cross bar of each apron, a ratchet and pawl on said rod for locking the rod to hold the fingers in their open position, and a stationary cam arranged in the path of the pawls of the several sets of devices adjacent to said transmission cylinder for releasing said fingers to grip a blank at the gap of said gumming cylinder, and means including toothed segments for openings the gripping devices for releasing said blank at a predetermined point in the travel of said conveyer.
5. The combination in a blank gripping apron conveyer of an endless traveling conveyer arranged to receive the blanks from a blank feeding or a blank gumming cylinder, said conveyer being equipped with cross bars, canvas aprons between said cross bars, a number of sets of gripping devices adapted to respectively and successively engage the blanks to facilitate their removal from the cylinder, each set of devices including a spring-actuated rod attached to said cross bars, gripping fingers mounted on said rod, a ratchet wheel mounted on said rod, a pawl arranged to lock said rod to hold the fingers in an open position, a stationary cam arranged in the path of the pawls of the several sets of devices for unlocking said fingers whereby said spring causes said fingers to fly over and grip a blank against its cross bar, and means for automatically returning the rod to raise the fingers to release said blank from said cross bar, a shaft on which said canvas aprons are supported at one end, means for supporting said conveyer at its opposite end, a transmission cylinder mounted on said shaft having a gap in which said bars and grippers fit and rotate with said cylinder, and means including mutilated gearing by which said rod transmission cylinder and said conveyer rotate in unison with said blank feeding or with said gumming cylinder to remove the blanks therefrom.
6. The combination in a blank gripping intermittently traveling or endless apron conveyer, provided with a transmission cylinder arranged to receive blanks, said conveyer being equipped with a plurality of cross bars having panels or aprons between them of any suitable material, a plurality of sets of gripping devices mounted on each alternate cross bar, adapted to respectively and successively engage the blanks at the blank feeding means, each set of devices including a spring-actuated rocking rod, blank gripping fingers mounted thereon arranged to grip the blanks against their respective cross bar, a ratchet and pawl for locking the rod to hold the fingers in their open position, a stationary cam arranged in the

6

path of the pawls of the several sets of devices for unlocking purposes, means for automatically turning the rocking rod to open the fingers to release the blanks, said means including a pinion fast on the rod, gear teeth mounted on a reciprocating lever arranged to be engaged by the pinion, means for actuating the gear teeth at properly timed intervals to impart the necessary movement to the spindle, said last named means including a cam actuated rock arm and lever mechanism, said transmission cylinder having a gap in which said cross bars and fingers fit and rotate with said cylinder, 10 said conveyer and its cylinder being arranged to rotate with an intermittent movement so timed that they stop and grip the blanks at the feeding means and feed them onto the canvas aprons as they feed around said transmission cylinder.

15 7. The combination of a blank gripping apron conveyer with an operative blank feeding means, said conveyer comprising a transmission gapped cylinder arranged to receive the blanks from said feeding means 20 in the gap of the transmission cylinder, said conveyer being equipped with blank gripping means for automatically and successively actuating the gripping mechanism to 25 release the blanks at a predetermined point in the travel of the conveyer, said means including a reciprocating lever having a toothed segment at its free end, a segment of a pinion on the gripping mechanism, a 30 link connection at one end of said toothed segment, a rock arm connected at one end to said link and at its opposite end to a connecting rod, a rock arm connected at one end to said connecting rod, and a cam engaging the opposite end of said rock arm.

35 8. In a blank gripping apron endless conveyer, the combination of a supporting frame, sprocket wheels mounted on said frame, a conveyer having a blank receiving 40 station and a blank releasing station, said conveyer comprising a pair of side chains mounted on said sprocket wheels, cross bars extending in pairs transversely across said chains and arranged to support a fabric 45 panel or canvas apron between each pair of area enough to receive and support the largest size blanks the machine will gum, a transmission cylinder at the blank receiving end of said conveyer concentric to its adjacent sprocket wheels, said cylinder being 50 provided with a gap in which said cross bars fit and rotate with said cylinder, means for gripping and holding blanks on each apron at the gap of the cylinder, and means 55 for releasing the blanks at the discharging station of the conveyer.

60 9. In a blank gripping apron conveyer, the combination, of a supporting frame, sprocket wheels mounted on said frame, a 65 conveyer having a blank receiving station

and a blank releasing station, said conveyer comprising a pair of side chains mounted on said sprocket wheels, cross bars extending in pairs transversely across said chains and arranged to support a fabric panel or canvas apron between each pair of bars, a transmission cylinder at the blank receiving end of said conveyer concentric to its adjacent sprocket wheels, said cylinder being provided with a gap in which said cross bars fit and rotate with said cylinder, means for gripping and holding blanks on each apron at the gap of the cylinder, and means for releasing the blanks at the discharging station of the conveyer.

10. In a blank gripping apron conveyer, the combination, of a conveyer, the cross bars and canvas aprons on said conveyer, a shaft having a partial rotative movement mounted on said cross bars, a canvas apron secured to said cross bars, blank finger pickers mounted on said shaft and spring controlled to resiliently spring against and grip the advancing edge of a blank, a pawl controlled ratchet wheel mounted on said shaft and arranged to lock said fingers in an open position, means including a cam positioned adjacent to said gapped cylinder for tripping the pawl to allow the fingers to spring forward and grip the advancing edge of a blank against its supporting cross bar, and means including gearing and cam controlled mechanism for releasing each blank from its finger pickers at the discharge end of the conveyer.

11. In a blank gripping apron conveyer, the combination with any suitable blank gumming means, of the endless traveling fabric apron conveyer, the blank gripping devices extending transversely across the conveyer, means including a coöperating cam and spring mechanism for operating the grippers to grip the blanks against the aprons, means including toothed segments for releasing the gripping devices from the blanks during the operation of the conveyer, and means including mutilated gearing for automatically stopping the travel of the conveyer during the gripping and releasing periods.

12. In a blank gripping apron conveyer for gumming machines, blank feeding and gumming mechanism in combination with means for tempering the blanks and conveying them from the gumming mechanism, said tempering and conveying means comprising an endless conveyer traveling by a blank gripping station and a blank releasing station and provided with a plurality of canvas aprons spaced a predetermined distance apart between cross bars and arranged to receive each blank from the gumming mechanism, said endless conveyer having a coöperating transmission cylinder provided with a gap and onto and against the

peripheral surface of which the aprons roll as said cylinder and conveyer rotate together, each of said aprons being provided with a set of blank gripping finger pickers 5 adapted to grip each blank as it leaves the gumming mechanism, said blank gripper being arranged to fit onto the gap of said cylinder and rotate with it and to grip the blanks when in the gap of said cylinder, and 10 means including a wet member for imparting a moisture temper to the dry side of the blanks as they rest on said aprons, whereby

said canvas aprons are saturated with water as they feed onto the peripheral surface of said transmission cylinder.

15

In testimony whereof we affix our signatures in presence of two witnesses.
